UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT.

SPECIFICATION forming part of Design No. 27,513, dated August 10, 1897.

Application filed December 26, 1896. Serial No. 617,117. Term of patent 7 years.

To all whom it may concern:

Be it known that I, FREDERICK W. CHESSON, a citizen of the United States, residing at Waterbury, in the county of New Haven and State of Connecticut, have invented and produced a new and original Design for Metal Mounts, of which the following is a specification, reference being had to the accompanying drawings, in which—

10 Figure 1 is an elevation, and Fig. 2 a plan, of my design.

The general configuration of the metal mount is round; and the leading features of my design consist in the cylindrical body portion, the adjoining semicircular bead, the conical portion, the bands, cove, bead, and contracted end, as shown.

The cylindrical body is shown at *a*, the adjacent semicircular beads at *b b'*, the conical portions at *c c'*, the coves at *d d'*, the beads at *e e'*, and tapering contracted ends at *f f'*, and the intermediate bands at *2 2* and *3 3*.

What I claim is—

The design for a metal mount, substantially as shown and described.

Signed by me this 17th day of December, 25
A. D. 1896.

F. W. CHESSON.
